UNITED STATES PATENT OFFICE

CARL W. CANNON, OF ANDOVER, MASSACHUSETTS

MAILING CASE

Application filed February 25, 1928. Serial No. 257,025.

This invention relates to what are known as mailing cases used for sending small articles through the mail.

It especially relates to the address tags and devices for attaching them to such a mailing case.

Its particular advantages are that small articles of merchandise or samples can be shipped for examination or approval and if unsatisfactory can be readily returned in the same mailing case, with part of the same tag, or the receipt of the article can be acknowledged by using part of the tag, or an order for a larger quantity can be given by returning part of the tag itself.

It also, in its preferred form, affords a very convenient package for mail carriers, one which can be used in the air mail for dropping out of the air on to a designed spot and and which will land right side up, usually penetrating a short distance into the ground or grass but in such manner that the tag will be exposed to view at the top of the package where it can readily be seen and therefore found.

In the drawings, Fig. 1 is a vertical sectional view of my preferred type of mailing case with my preferred type of double tag attached in the preferred manner.

Fig. 2 is a plan view showing one end of a mailing case with a somewhat different manner of attaching a double tag.

Fig. 3 is an elevation showing part of a shipping crate or mail bag in which a number of my preferred type of shipping cases are carried in the preferred manner.

Fig. 4 is a plan view of the return or reply part of a tag such as shown in Figs. 1 and 2.

Fig. 5 shows a double tag folded crosswise instead of endwise.

Fig. 6 is an elevation showing my preferred form of mailing case or mailing tube with the parts separated.

Fig. 7 is a fragmentary elevation partly in section showing part of a shipping case with a slightly different form of clip and tag.

Fig. 8 is a plan view of Fig. 7.

Fig. 9 is a view similar to Fig. 7 with a slightly different clip and tag.

Fig. 10 is a plan view of Fig. 9.

Fig. 11 is a view like Fig. 7 of a modified form of attaching clip and tag.

Fig. 12 shows a pointed tubular case.

In the drawings, A represents a male tubular section which may preferably be made of hard rubber, fiber, paper or similar material, closed at one end 10, and around its open end 11 being threaded at 12.

B represents a female tubular section closed at one end 20 and inside its open end 21, which is of a size to receive tube A, threaded at 22 to receive and engage the threaded end 12 of section A.

C represents a spring clip fixed at one end 30 to the outside of female section B and thence bent outward at 32 to form a stop to engage part of a tag D and prevent it from being pulled off. From thence it extends along at 31 parallel with the part B and terminates in a ball 34 which is so attached that it forms an end at 33, such ball touching the surface of the part B.

Such a ball serves as a stop to help prevent the end such as 44 of tag D from slipping past, and also makes it easier to pass the end of the spring clip through the holes in the tag.

D is an address tag upon which an address such as 140 may be written, and which has preferably three alined holes 41, 42 and 43, of which preferably the one nearest the middle that is 43, is the largest. The free end 34 of clip C is shown in Fig. 1 as passed first through 43 then 42, and then 41, and is shown in Fig. 2 as passed through in the opposite direction starting with 41. In either case, the tag D will be held flat and snug, in the first case extending out beyond the part B and, as shown in Fig. 2, extending down along the part B towards part A.

I prefer to use a double tag having alined at each end three holes 41, 42, 43 and 141, 142, 143 of such size and in such position that when the tag is folded centrally the three holes in each end will register with those in the other end. The clip such as C is therefore preferably alternately passed through each pair of registering alined holes.

As shown in Fig. 5 however, I may use a

double tag R folded lengthwise at 72 to make two parts 70 and 71 having the alined holes which when the tag is folded at 72 register in pairs 73, 75 and 74, 76.

5 The part 32 of the clip extends outwardly in such manner that some part of the tag as for instance in Fig. 1, one end of the hole 43 and in Fig. 2 one end of the hole 41 will engage it.

10 Where a fairly stiff tag is used, this engagement prevents the tag from being readily rubbed off or slipped off as it is necessary to lift either the part 40 shown in Fig. 1 or the part 44 shown in Fig. 2 in order to 15 readily slip it off.

I prefer to use the long double tag having one part 1 and the other part 2 with a cross-wise fold at 40 between them, and free at their other ends 44 or 144. With this device, the name of the receiver such as A. B. See can go on the outside of the part 1, and when the article is received, the whole tag can be removed and the part 1 torn off at the fold 40 leaving the part 2 to be returned to 20 the sender or to be used in reshipping the case or mailing tube represented by A and B.

25 As shown in Fig. 3, I prefer the arrangement shown in Fig. 1 because when these shipping cases are stuck in a box M or mail carrier's bag the tags D, D, D stick up where they can readily be seen, and on account of the shoulder 32, the cases A, B can be pulled out by the tags. Their ends may be round as at 3 or sharpened 4.

30 As shown in Figs. 7 and 8, I can use a shipping case H which may be a tube or of any shape, but should be of relatively stiff material to which a spring clip K is fixed at one end. At this fixed end, clip K extends 40 outwardly at a right angle to form a tag stop 55, and thence at 56 it extends along case H to its free end 57 which is bent down in contact with the surface of case H, and thence is bent slightly up to facilitate slipping on 45 the tag G¹, G². This tag is of the double type similar to the first tag D and is folded along the middle 58 and having the two free ends 59 and 159. Tag G¹, G² instead of three pairs of holes has two alined pairs of holes which register when the tag is folded. The holes 50 and 52 pass through one fold, and 51 and 53 pass through the other fold so as to register with 50 and 52 when the tag is folded. In this case, the free ends 59, 55 59 stick out beyond the holes 50, 51 while the holes 52 and 53 of the tag bear against tag stop 55 and hold the tag in place.

60 In Figs. 9 and 10, I shew attached to case H, a spring clip P which is fixed thereto and forms the tag stop 62 from whence it extends along at 63 substantially parallel with the surface of case S, terminating in a ball 64 which extends in and touches the surface of case H when there is no tag between them.

65 The tag L is shown as being single instead

of double, and of having two alined holes 60 and 61 through which clip P passes until the end 65 of tag L abuts on the stop 62.

In Fig. 11, I show attached to case S, a 70 spring clip T formed, at its end which is fixed to case S, with the tag stop 80 and extending therefrom through the holes 84, 85 and 86 in the single tag O along case S thence in at 82 approximate the case S and thence out and around as a hook 83.

75 Of course this construction can be used also with a double tag with two or more pairs of alined holes. It is useful in some cases because the hook makes it almost impossible for the tag to become detached without manual assistance.

80 In Fig. 12 I show my device adapted especially for the air mail. The tubular case V is pointed at 90 and has a screw cap 91 at its other end. It has oppositely disposed 85 spring clips 92 and 93 which hold in place the tags 94 and 95.

85 This case will drop straight and true like an arrow and its point 90 will penetrate the ground, grass or underbrush and will thus 90 keep tags 94, 95 sticking up where they can be seen.

95 Another advantage of the points 3, 4 shown in Fig. 3 and 90 is that they can more easily be pushed between other articles of mail into a mail bag than if the ends are blunt like 10.

I claim:

1. The combination in a mailing case, of a male tubular section closed at one end and threaded around the open end; with a female tubular section closed at one end and threaded inside the other end, said threads engaging those on the male section; a spring clip fixed near one end to the female section and extending outwardly therefrom to form a tag stop and thence along the female section and its free end formed as a ball proximate said case; and an address tag folded cross-wise so that three holes alined lengthwise near one end of one part register with similar alined holes in the other part, said clip passing alternately through each registering pair of alined holes, some part of the tag being in engagement with the tag stop. 100

2. The combination in a mailing case of a male tubular section closed at one end and threaded around the open end; with a female tubular section closed at one end and threaded inside the other end, said threads engaging those on the male section; a spring clip fixed near one end to the female section and extending outwardly therefrom to form a tag stop and thence along the female section and its free end extending in proximity to said case; and an address tag having three alined holes through which said clip passes, some part of the tag being in engagement with the tag stop. 105

3. The combination with a mailing case made of relatively stiff material; of a spring 110

clip fixed near one end thereto and which extends outwardly therefrom to form a tag stop and thence extends along and at its free end extends in proximity to the case; and an address tag so folded as to form two parts each having a plurality of alined holes which when the tag is folded register in pairs through which pairs of holes the clip passes alternately.

5 4. The combination with a mailing case made of relatively stiff material; of a spring clip fixed near one end thereto and which extends outwardly therefrom to form a tag stop and thence extends along and at its free end extends in proximity to the case; and an address tag having a plurality of alined holes through which the clip passes, some part of the tag being in engagement with the tag stop.

10 5. The combination in a mailing case, of a male tubular section pointed at one end and threaded around the open end; with a female tubular section closed at one end and threaded inside the other end, said threads 15 engaging those on the male section; a spring clip fixed near one end to one of the sections and extending outwardly therefrom to form a tag stop and thence along the case and at its free end extending in proximity to said case; and an address tag having a plurality of alined holes through which said clip passes, some part of the tag being in engagement with the tag stop; said tag extending beyond the end of the case.

20 6. The combination in a tubular mailing case pointed at one end; of a spring clip fixed near one end thereto and extending outwardly therefrom to form a tag stop and thence along the case and at its free end 25 extending in proximity to said case; and an address tag having a plurality of alined holes through which said clip passes, some part of the tag being in engagement with the tag stop; said tag extending beyond the end 30 of the case which is opposite the pointed end.

35 7. The combination in a mailing case, of a male tubular section closed at one end and threaded around the open end; with a female tubular section closed at one end and threaded inside the other end, said threads 40 engaging those on the male section; a spring clip fixed near one end to one of the sections and extending outwardly therefrom to form a tag stop and thence along the case and at its free end 45 extending in proximity to said case; and an address tag having a plurality of alined holes through which said clip passes, some part of the tag being in engagement with the tag stop.

50 8. The combination in a tubular mailing case; of a spring clip fixed near one end thereto and extending outwardly therefrom to form a tag stop and thence along the case 55 and at its free end extending in proximity to

said case; and an address tag having a plurality of alined holes through which said clip passes, some part of the tag being in engagement with the tag stop.
